VIBRATING-HEARTH FURNACE

Dee A. Knight, Lawson, Cole.

Application January 26, 1950, Serial No. 140,659

4 Claims. (Cl. 263—21)

1

This invention relates to furnaces of reverberatory type adapted for the heat treating of various materials for diverse particular purposes and has as a primary object the provision of an improved such furnace adapted and arranged for automatically continuous treatment of a material flow therethrough as distinguished from intermittent or batch operation.

A further object of the invention is to provide improved means for automatically feeding material under heat treatment along and across the heat-exposed hearth of a reverberatory furnace.

A further object of the invention is to provide improved means automatically operable to effect feed of material under heat treatment along and across the heat-exposed hearth of a reverberatory furnace and selectively adjustable to regulate and vary the rate of such feed throughout a range appropriate for materials of varying form, nature, and densities.

A further object of the invention is to provide improved means for automatically and continuously discharging treated material from a continuous-type reverberatory furnace.

A further object of the invention is to provide improved means for automatically and continuously feeding material to be treated to and for translation through a continuous-type reverberatory furnace.

A further object of the invention is to provide improved means for preheating incoming feed material as an incident of its automatically continuous delivery to and within a continuous-type reverberatory furnace.

A further object of the invention is to provide a vibrating, material-translating hearth in operative association within and in effective exposure to the heat circuit of a reverberatory furnace.

A further object of the invention is to provide an improved construction of and selectively-adjustable operative mounting for a vibrating, material-translating hearth in a reverberatory furnace.

With the foregoing and other objects in view, my invention consists in the construction, arrangement, and combination of elements as hereinafter set forth, pointed out in my claims, and illustrated by the accompanying drawings, in which:

Figure 1 is a side elevation of a typical reverberatory furnace as equipped and arranged to give effect to the principles of the invention, certain adjuncts being shown in broken lines and a portion of the stack being broken away to con-

2

serve space. Figure 2 is a front end elevation of the installation according to Figure 1, an upper portion of the structure being broken away to conserve space. Figure 3 is a vertical section, on an enlarged scale, taken longitudinally of the installation on substantially the indicated line 3—3 of Figure 2 with certain elements broken away to conserve space. Figure 4 is a horizontal section through and on substantially the indicated line 4—4 of Figure 3. Figure 5 is a transverse section taken substantially on the indicated line 5—5 of Figure 3. Figure 6 is a fragmentary, detail section, on a further enlarged scale, taken substantially on the indicated line 6—6 of Figure 3. Figure 7 is a fragmentary, detail section, on the same scale as Figure 6, taken substantially on the indicated line 7—7 of Figure 3. Figure 8 is a fragmentary, detail section, on the same scale as Figure 6, taken substantially on the indicated line 8—8 of Figure 1.

Reverberatory furnaces of the general type disclosed in my copending application for patent of the United States, Serial No. 109,020, Series of 1948, are extensively in use for the heat treating of a variety of materials including minerals, organic food products, chemical compounds, and the like, to variously effect roasting, drying, dehydrating, sintering, expanding, and exfoliating thereof. Such furnaces are characterized by a chamber enclosing a hearth, a source of heat discharging within the chamber, and a heat travel path or circuit traversing upper and lower faces of the hearth for appropriate temperature elevation of a charge upon the hearth. Conventional furnaces of the type noted are generally adapted for intermittent or batch operation with a consequent limitation of their efficiency and availability for the treatment of certain materials, and it is to the provision of a vibrating hearth in association with such a furnace and operable to translate material under treatment continuously through such furnace that the instant invention is primarily directed.

In the drawings, a typical reverberatory furnace is illustrated as a generally rectangular, closed chamber comprised from rigidly interrelated side walls 10, rear end wall 11, front end wall 12, roof 13, and floor 14. The sides, end walls, and roof may be of any desired heat-resisting construction appropriate to withstand the temperatures developed interiorly of the chamber, the illustrated construction typifying the use of spacedly-parallel, inner and outer metal shells constituting the furnace sides, end walls, and roof in an arrangement providing for circulation

of cooling fluid between the shells or for heat-insulation of the chamber by means of suitable material charged within and filling the space between the shells. Whatever may be the particular furnace wall and roof construction employed, the said walls close against a rigid, suitably-supported imperforate floor conveniently constituted from a metal sheet or panel. Giving operative effect to the principles of a reverberatory furnace arranged to heat both upper and lower surfaces of a hearth therein, a flue 15 opens through a lower portion of the furnace rear wall 11 and communicates with a stack 16 in a manner to exhaust heat and products of combustion from the furnace chamber and through said stack, while burners 17, or equivalent sources of high temperature gas flow, are mounted in and for delivery through an upper portion of the chamber front wall 12, so that, a hearth member being provided longitudinally of the chamber in end-spaced relation with the front wall 12 and to substantially close against the rear wall 11 above the flue 15, a flow path or circuit for the high temperature emanations from the elements 17 is established within the chamber and longitudinally of the hearth upper and lower surfaces. In the treatment of certain materials, it is wholly expedient that the high temperature supply to the furnace be developed through direct combustion within the furnace chamber of fuel products delivered through the elements 17, as is the case when said elements or burners are fed by hydrocarbon fuels, combustible gases, powdered coal, and the like, while in the treatment of certain other materials impingement of flame and products of combustion against the material under treatment is to be avoided, in which case the elements 17 may typify input nozzles for the delivery of previously-heated, high temperature air and gas streams to and interiorly of the furnace chamber.

All of the foregoing is largely conventional practice and merely typical of a furnace operative arrangement wherein and wherewith the improvements hereinafter described are effectively and advantageously employable.

In accordance with and to give effect to the principles of the instant invention, a hearth 18, preferably and conveniently in the form of a flat, shallow, metal tray having upstanding long margin flanges and of appropriate size, is operatively mounted longitudinally of the furnace chamber in spaced relation of its forward end rearwardly from the chamber front wall 12, in close adjacency of its rearward end relative to the chamber rear wall 11, and in clearing relation of its long side margins relative to the chamber side walls 10. The hearth 18 is designed to vibrate within and relative to the furnace chamber, to which end a shaft 19 is engaged transversely beneath and to support the midlength of said hearth and is extended at its ends perpendicularly through the chamber side walls 10 and exteriorly of said side walls through collars 20 carried by the lower ends of hanger assemblies 21, hereinafter more particularly described. To accommodate vibratory play of the shaft 19 relative to the chamber side walls 10 without extension of vibration to said side walls, the side wall apertures accommodating the shaft are somewhat larger than the shaft itself, as is clearly shown in Figure 7, and plates 22 fixed to and radially of the shaft 19 in appropriate size slidably close over the shaft-accommodating apertures in bearing engagement against the in-

ner and outer faces of the intersected chamber side wall to minimize heat outflow from the chamber about the shaft ends. The hanger assemblies 21 supporting the shaft are identical and each thereof comprises a threaded stem 23 adjustably engaging through an outer end of a bracket 24 fixed to and projecting laterally from the side wall 10 upper margin, a turnbuckle 25 included in and for length adjustment of the stem 23, a vibration-absorbing unit 26, of any desired particular construction, on the lower end of and extending the length of said stem 23, and an eye 27 linking the lower end of each unit 26 with the adjacent shaft-supporting collar 20. As is readily apparent, provision of the hanger assembly 21 in the form and construction shown and described serves to effectively support the shaft 19 through and relative to the furnace chamber in a manner permitting of shaft and hearth limited oscillation relative to said chamber and adjustment of the shaft end positions within the range of the clearance between the shaft and its accommodating apertures through the chamber walls. Manifestly, to develop the desired heat circuit within the furnace chamber, the shaft 19 is positioned to dispose the hearth 18 somewhat above the flue 15 intersection with the chamber rear wall 11.

To further support the hearth 18 and to determine the operating attitude of said hearth longitudinally of the furnace chamber, a shaft 28 is engaged beneath and inwardly adjacent each end of said hearth to traverse the furnace chamber in spaced parallelism with the shaft 19, each of the shafts 28 being extended at each end to intersection of the chamber side walls 10 through vertically-elongate, arcuate slots 29 whereof the center of curvature is coincident with the axis of the shaft 19. The slots 29 preferably extend above and below the horizontal plane including the axis of the shaft 19 and are of such altitudinal extent as may be appropriate or desired for angular adjustment of the hearth 18 in any given installation, and suitably-arcuate plates 30 fixed to the shafts 28 in slidably bearing engagement with the inner and outer faces of the chamber walls intersected by said slots are disposed to reciprocate in clips 31 fixed to the chamber wall faces and thereby close the slots 29 against heat escape therethrough. Outer ends of the shafts 28 engage with and through collars 20 on the ends of hanger assemblies 21 depending in fixed, adjustable relation from brackets 24 in the manner previously described, thus mounting the shafts 28 for oscillation together with the hearth 18 and shaft 19 in a clearance of the shafts 28 relative to their slots 29 adequate to accommodate a desired oscillatory range. Provision of the arcuate slots 29 to accommodate the shafts 28 in their intersection of the chamber side walls 10 and support of the shaft 28 exterior ends by the hanger assemblies 21 permits selective elevation of either end of the hearth 18 to dispose said hearth at an angular inclination to the horizontal longitudinally of the furnace chamber, as is clearly indicated by broken lines in Figure 3. Thus, the hanger assemblies 21 at the forward end of the furnace chamber may be shortened to lift the forward end of the hearth 18 and to tilt said hearth about the axis of the shaft 19 when and as the hanger assemblies supporting the shaft 28 at the rearward end of the hearth are correspondingly lengthened; such adjustment elevating the hearth forward end and depressing the hearth

rearward end in an angular relation with the horizontal wherein the hearth assembly is free to oscillate. Conversely, the hanger assemblies supporting the rearward shaft 28 may be shortened and the assemblies supporting the forward shaft 28 correspondingly lengthened to longitudinally tilt the hearth in an elevation of its rearward end and a corresponding depression of its forward end while retaining the oscillatory character of the assembly.

Suspended interiorly of the furnace chamber in the manner shown and described, the hearth 18 is mounted for oscillation altitudinally and longitudinally of said chamber within the limits imposed by the size of the side wall apertures accommodating the shafts 19 and 28 and in any of its angularly-adjusted positions, and a periodic oscillation on the order of a vibration is imparted to said hearth during operation of the furnace through the agency of vibrator units or mechanisms 32, of any appropriate construction and type, fixedly base-mounted exteriorly and adjacent the side walls of the furnace in operative engagement with ends of the shaft 19 extending beyond the shaft-associated collars 20. The vibrator units 32 are conventionally shown in a representation typical of such instrumentalities adapted for electrical mechanical, or pneumatic powering and for regulation of the length and intensity of their reciprocatory stroke, such units being known and available, and a practical and feasible association of such units with the shaft 19 is developed through a mounting of the units radially of the shaft and at a forward and upward inclination to the horizontal such as serves through engagement of the unit reciprocable element ends with said shaft to move the shaft 19, and the hearth 18 carried thereby, upwardly and forwardly of the furnace chamber as a consequence of unit 32 extension, or outward stroke, and to move said shaft and hearth downwardly and rearwardly of the chamber as a consequence of unit 32 contraction, or inward stroke; such longitudinal oscillation of the hearth operating to induce translation of granular material charged onto the hearth upper surface from the rearward and to the forward end thereof. The motion imparted to the hearth 18 through the agency of the units 32 is a rapid, cyclic, short-travel vibration operable to spread and agitate a granular charge on said hearth as well as to translate the charge along the hearth, and adjustment of the hearth longitudinal attitude, as above explained, supplements the adjustability of the unit 32 stroke to permit regulation of the rate of material travel along the hearth, so that, through the accelerating or retarding influence of gravity resulting from hearth inclination, various materials may be caused to travel across the hearth length at a rate appropriate to develop the desired degree of material exposure while on the hearth, and with the hearth transverse aspect maintained horizontal, the so-translated material is caused to spread evenly in a state of constant agitation across the hearth width as it travels from end to end thereof.

Feed of material to be treated to the rearward end of the hearth 18 is conveniently had through a slit opening transversely of the roof 13 inwardly adjacent the furnace rear end wall 11 in operative registration with the open lower end of a jacketed stack 33 upstanding from and above said roof, the upper end of said stack 33 communicating through a flue 34, furnished with a damper 35, with the exhaust stack 16 for the selective bypassing of hot gases from the furnace chamber

through the stack 33. The material to be treated may be introduced into and for gravity drop through the stack 33 in any manner and by any means suited to the character of a given material, an effective and generally-appropriate arrangement for such purpose being illustrated as a feed plate 36 slidably reciprocable in a horizontal disposition intersecting one wall of the stack 33 with its inner lip interiorly overhanging the stack passage, a vibrator unit 37, the same as or functionally analogous to the units 32, mounted upon the furnace roof 13 and operatively engaging the plate 36 to vibrate the latter for travel of granular material thereover and from the outer to the inner areas thereof, and means, such as a hopper 38, for supply of material to the plate 36 outer area. The discharge throat of the stack 33 opens interiorly of the furnace chamber against a baffle 39 closing against the roof 13 at the forward margin of the stack throat and inclining rearwardly and downwardly of the chamber with its lower margin spaced forwardly from the furnace rear end wall 11. The baffle 39 serves to deflect material incoming through the stack 33 toward the furnace rear end wall, to somewhat retard the free fall of the incoming material, to direct heat emanating from the elements 17 downwardly toward the rear end of the hearth 18, and to partially obstruct the entrance of hot gases within and for travel through the stack 33. As will be apparent, manipulation of the damper 35 may be had to permit a controlled flow of hot gases from the furnace chamber and through the stack 33 for the preheating of material fed through said stack; such preheating of the material being of significance in certain operations and operating to reduce the effective time of material transit across the hearth 18. Fixed to the furnace rear end wall 11 in spaced relation with and beneath the free lower margin of the baffle 39, a second baffle 40 outstands in a forward and downward inclination to overhang the rearward end of the hearth 18 and direct the material feed onto said hearth without loss of material between the hearth rear end and adjacent furnace end wall.

Material heat treated upon and translated longitudinally along the hearth 18 as a consequence of hearth vibration passes over the forward end of said hearth and falls through the space between the hearth forward end and furnace front end wall 12 to collection in means effective to deliver the treated material exteriorly of the furnace chamber. Manifestly, diverse, variously-powered structural organizations may be utilized to effect delivery of treated material from the furnace chamber, the particular such means illustrated and hereinafter described being but typical of functionally-analogous arrangements. As shown in the drawings, a straight, upwardly-opening trough 41, desirably arcuate in transverse section, is disposed transversely of the furnace chamber beneath and in position to receive the material discharged from the hearth forward end, said trough having a length exceeding the furnace chamber width and reciprocably intersecting the furnace side walls 10 in end extension therebeyond at such longitudinal inclination relative to the horizontal as may be appropriate in a given installation. The trough 41 is supported and suspended for longitudinal oscillation by means of links 42 operatively engaging between trough zones exteriorly adjacent the furnace side walls 10 and brackets fixedly carried by said walls above the trough, and a vibrator unit 43 base-

mounted exteriorly of the furnace in appropriate alignment with and adjacent one end of the trough 41 engages with the latter for continuous, cyclic, longitudinal vibration or oscillation of said trough as a consequence of unit 43 actuation; the trough 41 mounting and association with the unit 43 naturally being such as to apply trough vibration to translation of collected material along said trough and to delivery outwardly of the furnace through the trough end remote from the unit 43.

It is to be noted that the improvement illustrated and hereinabove elaborated provides an efficient, highly-adaptable, heat-treating furnace of reverberatory type wherein high temperatures of combustion may be either directly or indirectly applied both above and below a charge received upon and continuously travelling along a vibrating hearth in a manner permitting of continuous delivery of treated material from the furnace. The provision of an overhead feed to the furnace hearth through a stack functioning as a bypass for a portion of the furnace heat charge enhances the efficiency and steps up the effective capacity of the furnace, the angular adjustability of the hearth and the regulability of the associated vibrator units permit simple and effective control of the material flow rate through the furnace, and the construction and interassociation of elements comprising the improved organization conduce to uninterrupted service, simple maintenance, and expeditious repair.

Since many changes, variations, and modifications in the form, construction, and arrangement of the elements shown and described may be had without departing from the spirit of my invention, I wish to be understood as being limited solely by the scope of the appended claims, rather than by any details of the illustrative showing and foregoing description.

I claim as my invention:

1. In a reverberatory-type furnace having an enclosed furnace chamber defined by front, rear and side walls and a roof bridging therebetween, an exhaust passage through a lower portion of the chamber rear wall, heat-generating means delivering to said chamber through an upper portion of the chamber front wall, and means for feeding material to be treated through said roof inwardly adjacent said rear wall, a horizontal shaft loosely traversing the chamber side walls transversely of the chamber between the exhaust passage and heat delivery levels and well forwardly from said rear wall, altitudinally-adjustable hangers engaging the ends of said shaft exteriorly of the chamber to suspend the shaft for oscillation, vibrator units operatively engaging the exterior ends of the so-suspended shaft, a flat,

solid tray fixed to said shaft in operatively clearing adjacency of its side and rear end margins relative to the corresponding chamber walls with its front margin spaced inwardly from the chamber front wall, whereby to dispose said tray as a hearth positioned to receive the feed of material at its rearward end and arranged to direct heat flow within the chamber through the material infeed and to successively and longitudinally traverse the tray upper and lower surfaces, means for adjustably determining the longitudinal inclination of said tray relative to the horizontal, and means for collecting material discharged over the tray front margin and delivering the same exteriorly of the chamber.

5 2. The organization according to claim 1, wherein said shaft carries radial plates disposed to slidably close over inner and outer ends of the shaft-accommodating openings through the 10 chamber side walls.

15 3. The organization according to claim 1, wherein the means for adjustably determining the longitudinal inclination of the tray relative to the horizontal comprises supplementary shafts 25 spacedly paralleling and on opposite sides of said first shaft engaged beneath and adjacent the front and rear ends of the tray in loosely-intersecting relation with the chamber side walls, vertically-elongated, arcuate slots in the chamber 30 side walls for the loose accommodation of the supplementary shaft ends, radial plates on said supplementary shafts disposed to slidably close over inner and outer areas of said slots, and altitudinally-adjustable hangers swingably engaging 35 ends of said supplementary shafts exteriorly of the chamber.

4. The organization according to claim 1, wherein said exhaust passage connects with an exhaust stack exteriorly of the chamber, a bypass flue connects the chamber interior with said stack through the material-feeding means operable through the chamber roof, and a baffle in said flue is operable to regulate material-preheating outflow therethrough.
